P. F. KING

PLIER WRENCH

Filed Aug. 24, 1926

INVENTOR.

Percival F. King.

BY
Albert E. DeLancey
ATTORNEY

UNITED STATES PATENT OFFICE.

PERCIVAL FAULCNER KING, OF MIAMI, FLORIDA.

PLIER WRENCH.

Application filed August 24, 1926. Serial No. 131,232.

The invention generally relates to plier wrenches of the pivoted jaw type and primarily has for its object to provide a simple, inexpensive and compactly constructed plier wrench having exceptionally good gripping qualities and the quality of locking the jaws thereof to the gripping or clamped condition.

In its more detailed nature the invention comprises a fixed body having a fixed jaw and handle, a second jaw member being pivoted to the body to cooperate with the first jaw and a second handle member being pivoted to the body, said second jaw member having jaw closing and locking and jaw opening cam faces, and said second handle member having projections for engaging the jaw closing and locking cam face when moved in one direction to close and lock the jaws to a clamped condition, and for engaging the jaw opening cam face when moved in the other direction to open said jaws.

The invention still further resides in the novel details of construction, combination and arrangement of parts, all of which will be first fully described, then be particularly pointed out in the appended claims, reference being had to the accompanying drawing, in which:—

Figure 1 is a side elevation illustrating the plier wrench in the clamped condition.

Figure 2 is a view similar to Figure 1, the jaws being shown in the unlocked condition in full lines and in the open position in dotted lines.

Figure 3 is a plan view of the plier wrench shown in Figures 1 and 2.

Figures 4 and 5 are views similar to Figures 1 and 2 and illustrate a modified form of the invention.

In the drawings 1 is the fixed body which has the fixed jaw 2 and handle 3 and to which the movable jaw 4 is pivoted at 5.

The movable jaw 4 has a closing and locking cam face 6 and an opening cam face 7 the purpose for which will presently appear.

The handle 8 is pivoted as at 9 to the fixed body 1 and is provided with a heel 10 extended forwardly from the pivoted connection 9 to position for having the advance face 11 thereof in cooperative relation with the closing and locking cam face 6 of the movable jaw 4, and with a lug 12 in co-

operative relation with the opening cam face 7 of said jaw.

The cam face 7 of the movable jaw terminates with a stop heel 13 for engaging the lug 12 to limit the opening of the clamping jaws.

It will be observed by reference to Figures 1 and 2 of the drawing that by reason of the correlative positions of the pivots 5 and 9, the cam faces 6 and 7, the heel 10—11, 65 and the lug 12, each time the handles are forced together the clamping jaws 2 and 4 are very forcibly clamped together or upon a piece to be clamped, and automatically locked to such clamped condition against 70 inadvertent retraction. When the handles are separated the lock-clamp is broken and the jaws are forced apart.

In the form of the invention shown in Figures 4 and 5 the component parts of the 75 wrench are the same in number and are equipped with similar camming surfaces and engaging portions as in the form first described, the parts being slightly rearranged whereby to provide for an increased lever- 80 age in the clamping and locking action of the plier wrench and for easily breaking the locked condition and opening of the jaws of the said plier wrench.

In this modified form of the invention 85 those parts having like purpose and function to corresponding parts in the first embodiment bear the same reference numerals with the index letter *x* and therefore further detailed description of the second embodiment of the invention is thought to be unnecessary.

From the foregoing description taken in connection with the accompanying drawing, it is thought that the novel details of construction, the manner of use and the advantages of the invention will be readily apparent to those skilled in the art to which it relates.

What I claim is:

1. In plier wrenches, a body having a fixed jaw and handle, a movable jaw pivoted to the body, a movable handle pivoted to said body, said movable jaw and said movable handle having cooperating portions located above and other cooperating portions located below a line passed through said movable jaw and movable handle pivots and adapted to coengage to effect a clamping and locking of the jaws when the han- 100
105
110

dles are moved in one direction and to effect a release of the locking condition and an opening of the jaws when the handles are moved in the opposite direction.

5. 2. In plier wrenches, a body having a fixed jaw and handle, a movable jaw pivoted to the body, a movable handle pivoted to the body, said movable jaw having a cam face bearing acute angular relation to the 10 plane on which the movable jaw and handle pivots are located, and said movable handle having an extension for engaging said cam face when the handles are pressed toward each other to effect a clamping of the jaws whereby tendency to separate the jaws when 15 clamped will cause said cam face to act on said extension in a manner tending to draw the handles toward each other.

3. In plier wrenches, a body having a 20 fixed jaw and handle, a movable jaw pivoted to the body, a movable handle pivoted to the body, said movable jaw having a cam face positioned on a plane bearing acute angular relation to the plane on which the 25 axes of the movable jaw and handle pivots are located, and said movable handle having an extension for engaging said cam face when the handles are pressed toward each other to effect a clamping of the jaws, said

cam face being spaced a lesser distance from 30 the pivot of the movable jaw than the engaging end of the extension is spaced from the pivot of the movable handle.

4. In plier wrenches, a body having a fixed jaw and handle, a movable jaw pivoted 35 to the body, a movable handle pivoted to the body, said movable jaw having a cam face bearing acute angular relation to the plane on which the movable jaw and handle pivots are located, and said movable handle 40 having an extension for engaging said cam face when the handles are pressed toward each other to effect a clamping of the jaws, whereby tendency to separate the jaws when clamped will cause said cam face to 45 act on said extension in a manner tending to draw the handles toward each other, said cam face and extension engaging portions being positioned to one side of and in advance of the pivots and said movable jaw 50 and said movable handle having other portions located at the other side of and between the pivots and adapted to engage when the handles are separated to release the clamped condition and effect a separation of the jaws.

PERCIVAL FAULCNER KING.
